[57] CLAIM

The ornamental design for a tilttable desk lamp, as
shown and described.

DESCRIPTION

FIG. 1 is a perspective view of a tilttable desk lamp
showing our new design;

FIG. 2 is a top plan view thereof;

FIG. 3 is a side elevational view thereof, the other side
elevational view being a mirror image thereof;

FIG. 4 is a front elevational view thereof;

FIG. 5 is a rear elevational view thereof; and,

FIG. 6 is a bottom plan view thereof.
